Primary Examiner — Jonathan J Han*(74) Attorney, Agent, or Firm* — Marshall A. Lerner; Steven J. Kim; KLEINBERG & LERNER, LLP(57) **CLAIM**

The ornamental design for a shoe upper as shown and described.

DESCRIPTION

FIG. 1 is a front perspective view of a shoe upper in accordance with my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines shown in the drawings represent portions of the shoe upper as well as environmental structure of the sole and form no part of the claimed design.
